(57) **CLAIM**

The ornamental design for a headwear visor with replaceable band, as shown and described.

DESCRIPTION

FIG. 1 is a front elevation view of a headwear visor with replaceable band of the present design;

FIG. 2 is a right side elevation view of the headwear visor with replaceable band of the present design, the left side being a mirror image thereof;

FIG. 3 is a top plan view of the headwear visor with replaceable band of the present design;

FIG. 4 is a bottom perspective view of the headwear visor with replaceable band of the present design;

FIG. 5 is an enlarged rear perspective view of the headwear visor with replaceable band of the present design;

FIG. 6 is a front elevation view of the headwear visor of the present design, with the replaceable band removed for clarity of illustration;

FIG. 7 is a right side elevation view of the headwear visor of the present design, the left side being a mirror image thereof, with the replaceable band removed for clarity of illustration;

FIG. 8 is a top perspective view of the headwear visor of the present design, with the replaceable band removed for clarity of illustration;

FIG. 9 is a front elevation view of the replaceable band of the present design;

FIG. 10 is a rear elevation view of the replaceable band of the present design;

FIG. 11 is an enlarged rear perspective view of the headwear visor with replaceable band of the present design;

FIG. 12 is a top perspective view of the headwear visor with replaceable band of the present design, with the replaceable band removed for clarity of illustration;

FIG. 13 is a top perspective view of the headwear visor with replaceable band of the present design;

FIG. 14 is a front elevation view of the replaceable band of the present design; and,

FIG. 15 is a rear elevation view of the replaceable band of the present design.

The features shown in uniform broken lines form no part of the claimed design. This includes the uniform broken line patterns shown in FIGS. 9 and 14, and the uniform broken lines across the replaceable band shown in FIGS. 1-3, 5, 9-11, and 13-15. The non-uniform broken lines represent the boundaries of the design.
